8 Claims. (Cl. 143—32)

ABSTRACT OF THE DISCLOSURE

This relates to a chain saw guard having a substantially U-shaped cross section and normally overlying the upper run of the chain saw. The guard is pivotally secured to the chain saw so that as the chain saw is used, the guard is moved upwardly clear of the chain. Also a spring returns the guard to the shrouding position. A finger operated lever and cable and sheave assembly extending from one end of the lever to the guard, enables the guard to be elevated substantially at right angles when it is desired to use the chain saw without a guard.

This invention relates to new and useful improvements in guards for chain saws.

Chain saws are normally used for felling trees, removing of branches from felled trees, and cutting tree lengths into pulpwood lengths after the trees have been felled.

In all of these operations there is a danger to the operator inasmuch as the upper run of the chain is travelling forwardly. If this upper run inadvertently engages a branch or log while being operated, the chain saw "kicks back" and if the operator is unprepared, the momentum may carry the saw back far enough allowing this upper edge to strike the operator.

This is particularly true in the operation of felling trees when the saw is being held horizontally or upon its side.

We have overcome this dangerous situation by providing a substantially U-shaped cross sectioned guard adapted normally to overlie the upper run of the chain saw and to prevent this upper run from engaging a branch or log as aforesaid. This guard is pivotally secured to the chain saw so that as the chain saw passes through the tree or log being cut, the guard is moved upwardly clear of the chain so that the chain pass clear through the log or tree being cut. As soon as the chain saw has been removed from the cut log, a spring returns the guard to the shrouding position.

However, it will be appreciated that under certain circumstances, it is desirable for the operator to be able to elevate the guard clear of the chain saw and we have provided structure for this purpose consisting of a finger operated lever and a cable and sheave extending from one end of the lever to the guard so that pressure upon one end of the lever elevates the guard substantially at right angles to the chain saw against the pressure of the aforementioned spring.

The principal object and essence of the invention is therefore to provide a device of the character herewithin described which increases the safety of the operation of a chain saw.

Another object of the invention in conjunction with the foregoing object is to facilitate the increase of production of an operator inasmuch as less precaution is required on the part of the operator in watching for inadvertent "kick backs."

A still further object of the invention is to provide a device of the character herewithin described which pro-

2

vides means whereby the operator can elevate the guard clear of the chain saw under certain circumstances.

A still further object of the invention is to provide a device of the character herewithin described which is easily mounted on conventional chain saws, is simple in construction, economical in operation, and otherwise well suited to the purpose for which its is designed.

With the foregoing in view, and all those objects, purposes or advantages which may become apparent from consideration of this disclosure and specification, the present invention consists of the inventive concept embodied in the method, process, construction, arrangement of parts, or new use of the same, as herein particularly exemplified in one or more specific embodiments of such concept, reference being had to the accompanying figures in which:

FIGURE 1 is a side elevation of our chain saw guard per se.

FIGURE 2 is a section of FIGURE 1 substantially along the line 2—2 of FIGURE 1, but with the device attached to a chain saw.

FIGURE 3 is a fragmentary section along the line 3—3 of FIGURE 1.

FIGURE 4 is a fragmentary section along the line 4—4 of FIGURE 1.

FIGURE 5 is a fragmentary section along the line 5—5 of FIGURE 1.

In the drawings like characters of reference indicate corresponding parts in the different figures.

Proceeding therefore to describe the invention in detail, reference should first be made to the accompanying drawings in which a conventional chain saw collectively designated 10 is shown in single line.

This chain saw comprises generally, a supporting structure or casing 11 containing a conventional source of power 11' and incorporating a fuel tank 12.

A chain saw assembly collectively designated 13 extends outwardly from the supporting structure 11 and comprises the vertically situated plate 14 around which an endless cutting chain 15 is journaled, said cutting chain being moved in the direction of arrow 16 by means of the source of power.

The chain saw assembly includes the lower run 17 and the upper run 18.

The guard collectively designated 19 comprises a substantially horizontal upper plate 20 and a pair of downwardly depending side plates 21, the side plates depending from the side edges 22 of the upper plate and being in spaced and parallel relationship one with the other. These side plates flare outwardly along a line 22' in FIGURE 1, the flare portion being numbered 22".

These side plates, when viewed in side elevation, are provided with partially curved edges 23 and these partially curved edges include a relatively straight edge portion 24 extending from adjacent the rear end 25 of the guard for a distance of approximately $\frac{2}{3}$ along the length thereof. The curve then increases in radius relatively sharply as at 25' for the last third of the length and terminates at the point 26 where it joins the front end of the upper plate 20.

A bracket 27 is secured to the framework by means of bolts 28 and extends upwardly upon one side thereof. This bracket is then angulated horizontally as at 29 and is provided with a vertical portion 30 situated to the rear and substantially above the aforementioned saw chain assembly 13.

A bolt 31 extends through the portion 30 of the bracket and normal to the plane of the chain saw assembly 13. The ends of this bolt pass through the side plates 21 of the guard adjacent the rear end 25 thereof and is secured to these side plates by means of nut 32 thus pivoting the guard to the bracket 27, bearing sleeve 31' being mounted on the bolt 31.

A reinforcing channel 33 embraces the rear portion 25 of the guard and is secured thereto and not only stiffens the guard at this point but adds additional material for the clamping of the guard to the bolt 31.

The rear end of the channel 33 is provided with edges 34 and 35 at right angles to one another and rearwardly of the pivot bolt 31. These engage the upper surface 36 horizontal portion 29 of the bracket 27 at the extremities of the pivotal movement of the guard and limit this pivotal movement so that the guard, when down, takes up the position shown in FIGURE 1.

The guard can also be pivoted around pivot bolt 31 to a position substantially at right angles to the normal position, and this position is being approached as shown in dotted lines in FIGURE 1.

The weight of the guard normally maintains the guard in the position shown in full line in FIGURE 1, and returns the guard to this position after it has been raised either during the cutting action of the chain saw or manually as will hereinafter be described.

The operation of the device as hereinbefore described, permits the operator to utilize the saw in the normal manner and as the edges 23 of the side plates are engaged by the sides of the cut being made, the guard is elevated against the weight of the guard due to the fact that the majority of the mass is forwardly of the pivot bolt 31.

In this connection note should be made of the outwardly flared or divergent portion 22" of the sides of the guard which assist in deflecting sawdust from the face of the operator.

The vertical portion 30 of bracket 27 is extended rearwardly in the form of bar 37 having a mounting portion 38 formed at right angles to the rear end 39 thereof. The lever 40 is pivoted intermediate the ends thereof to this mounting portion 38 by bolt 41 held in position by nut 42.

The rear end 43 of the lever extends rearwardly adjacent one handle 44 of the saw so that it can be engaged readily by the finger or thumb of the hand engaging this grip 44.

A cable 45 is secured to the extremity 46 of the lever 39 and this cable extends downwardly, around a sheave 47 journaled to bar 37 and thence upwardly and forwardly around a cylindrical sleeve 32' secured between side plates 21 of the guard and journaled the guard 19 to the bracket portion 30 by means of bolt 31. The extremity 45' of the cable is secured to the upper plate 20 of the guard after passing several times around the sleeve 32', depressing the lever portion 43, which causes the cable to raise the guard 19 into the position approached in phantom in FIGURE 1. Details of this portion of the device is shown in FIGURE 5.

Conversely, release of pressure from the lever portion 43 permits the weight of the guard to return the guard to the solid line position in FIGURE 1.

Since various modifications can be made to the invention herein described within the scope of the inventive concept disclosed, it is not intended that protection of the said invention should be interpreted as restricted to the modification or modifications or known parts of such concept as have been particularly described, defined, or exemplified, since this disclosure is intended to explain the construction and operation of such concept, and not for the purpose of limiting protection to any specific embodiment or details thereof.

What we claim as our invention is:

1. A guard for chain saws which includes supporting framework, a source of power in said framework, and an endless saw chain assembly extending from said framework and operable by said source of power, said saw chain assembly including an upper run of saw chain;

said guard comprising in combination a supporting bracket secured to said supporting framework and extending upwardly above and to the rear of said chain assembly, a substantially U-shaped cross section guard pivotally secured adjacent one end thereof to said supporting bracket and normally overlying the said saw chain upper run but in spaced relationship thereto, said guard including a substantially horizontal top plate and a pair of spaced and parallel side plates depending from the edges of said top plate, said side plates normally shrouding at least part of said saw chain upper run, and manually operable means mounted upon said supporting structure to selectively raise and lower said guard with relation to said saw chain upper run, said last mentioned means comprising a lever pivoted intermediate the ends thereof to said supporting structure, and cable and sheave means extending between one end of said lever and said guard.

2. The device according to claim 1 in which the pivotal securing of said guard to said supporting bracket comprises a bolt secured to said supporting bracket transversely thereof and extending through said guard adjacent the rear end of said guard, and bearing means journaled said guard to said bolt.

3. The device according to claim 2 which includes a cylindrical sleeve spanning the sides of said guard and being secured thereto, said sleeve being journaled upon said bearing means, one end of said cable being wrapped around said sleeve and being secured to said guard.

4. The device according to claim 1 in which the lower edges of said side plates, when viewed in side elevation, consist of a relatively straight portion extending downwardly and forwardly from the rear end of said side plates for approximately two-thirds of the length of said side plates and then curving upwardly and at an increased radius, for approximately the last third of the length of said side plates, the lower sides of said side plates being outwardly flared to act as sawdust deflectors, and a guard reinforcing channel secured over the rear portion of said guard.

5. The device according to claim 4 in which said last mentioned means comprises a lever pivoted intermediate the ends thereof to said supporting structure, and cable and sheave means extending between one end of said lever and said guard.

6. The device according to claim 4 in which the pivotal securing of said guard to said supporting bracket comprises a bolt secured to said supporting bracket transversely thereof and extending through said guard adjacent the rear end of said guard, and bearing means journaled said guard to said bolt.

7. The device according to claim 5 in which the pivotal securing of said guard to said supporting bracket comprises a bolt secured to said supporting bracket transversely thereof and extending through said guard adjacent the rear end of said guard, and bearing means journaled said guard to said bolt.

8. The device according to claim 4 which includes a cylindrical sleeve spanning the sides of said guard and being secured thereto, said sleeve being journaled upon said bearing means, one end of said cable being wrapped around said sleeve and being secured to said guard.
